UNITED STATES PATENT OFFICE

2,041,714

MINING APPARATUS

Morris P. Holmes, Claremont, N. H., assignor to
 Sullivan Machinery Company, a corporation
 of Massachusetts

Application June 9, 1931, Serial No. 543,145

28 Claims. (Cl. 262—28)

This invention relates to mining apparatus and more particularly to coal mining apparatus of the shear cutter type adapted to cut vertical kerfs in the coal.

5 An object of this invention is to provide an improved coal mining apparatus. Another object is to provide an improved coal mining apparatus of the shear cutter type adapted to cut vertical kerfs in the coal. A further object is 10 to provide an improved coal mining apparatus of the wheel mounted, track cutting type adapted to insert vertical or shear cuts in the coal. Still another object of this invention is to provide an improved track cutting mining machine having 15 improved kerf cutting mechanism and improved means for operating and guiding the kerf cutting mechanism during the cutting operation and for propelling the machine about the mine. Yet another object is to provide an improved shearing 20 machine of the self-propelled, truck mounted type wherein improved means are provided for moving and guiding the shear cutting mechanism relative to the truck during the cutting operation and for propelling the machine along 25 the mine trackway during transport. Still another object is to provide an improved shearing machine of the pivoted kerf cutter type having improved means for swinging the kerf cutter about its pivot and for feeding the kerf cutter 30 relative to the coal during the cutting operation. Still another object is to provide an improved coal mining machine of the so-called swivel shearer type wherein the kerf cutting mechanism is mounted on a guiding frame swivelly supported by a wheeled truck and having associated 35 therewith improved means for feeding the cutting mechanism relative to the guiding frame. These and other objects of the invention will, however, hereinafter more fully appear.

40 In the accompanying drawings there is shown for purposes of illustration one form which the invention may assume in practice.

In these drawings,—

45 Fig. 1 is a plan view of the illustrative embodiment of the improved mining apparatus.

Fig. 2 is a side elevational view of the apparatus shown in Fig. 1.

Fig. 3 is a transverse vertical sectional view taken substantially on line 3—3 of Fig. 2.

50 Fig. 4 is a horizontal sectional view taken substantially on line 4—4 of Fig. 3.

Fig. 5 is a detail sectional view taken substantially on line 5—5 of Fig. 3.

55 Fig. 6 is a horizontal sectional view taken substantially on line 6—6 of Fig. 2.

Fig. 7 is a longitudinally extending vertical sectional view taken substantially on line 7—7 of Fig. 6.

Fig. 8 is a longitudinally extending vertical sectional view taken substantially on line 8—8 of Figs. 1 and 3.

Fig. 9 is a longitudinally extending vertical sectional view taken substantially on line 9—9 of Figs. 1 and 3.

Fig. 10 is a detail sectional view taken substantially on line 10—10 of Fig. 8.

In this illustrative embodiment of the invention there is shown a coal mining apparatus of the wheel mounted, shear cutter type adapted to operate while supported by a mine trackway 15 mounted on wheels 2 adapted to run along a mine trackway 3. Suitably mounted on the truck frame for horizontal movement about a vertical axis is a guiding frame 4 having slidably guided 20 thereon kerf cutting mechanism generally designated 5. Suspended from the forward end of the guiding frame 4 beneath the guideways thereon is a horizontal motor 6 for driving the various mechanisms of the apparatus, and this motor 25 is so arranged on the guiding frame that it substantially counterbalances the weight of the kerf cutting mechanism when the latter is in its rear-most position as shown in Fig. 2. The guiding frame 4 is adapted to be swiveled into different 30 angular positions relative to the truck frame, and the kerf cutting mechanism is guided for movement longitudinally of the guiding frame during the cutting operation as hereinafter described. 35 If desired jacks may be associated with the guiding frame 4 to guard against tilting tendencies, but in practice the slack produced and the support of the bar by the coal render jacks unnecessary.

Now referring to the guiding frame 4 and its 40 swivel mounting on the truck frame, it will herein be noted that supported on the forward end of the truck frame directly above the front truck wheel axle is a swivel frame 7 having secured thereto beneath the same an annular frame or swivel bearing 8 carrying series of horizontal and vertical rollers 9 and 10 journaled on pins 11 carried by the frame 8, as shown in Fig. 3. The horizontal rollers 9 engage the inner periphery 45 of an annular guide or bearing housing 12 herein formed integral with a bearing frame 13 to which the side angle members 14 of the truck frame are secured and in which the front truck wheel axle is journaled, the axle being indicated 50 at 15. The vertical rollers 10 engage the bearing 55

surface of an annular member 16 attached to the bearing frame 13 and forming a trackway for the rollers 10. The rollers 10 may also engage the lower surface of a detachable ring frame 17 secured to the bearing housing 12. These elements cooperate to form a horizontal turntable structure on which the guiding frame 4 is mounted for horizontal swinging movement relative to the truck. As illustrated, rigidly attached to the swivel frame 7 at the outer sides thereof are angle members 18, 18 having attached to their upper flanges, guide plates 19, 19. These angle members 18, 18 extend a substantial distance forwardly and rearwardly of the turntable structure with the rearwardly extending portions thereof overlying, when the parts are in the position shown in Fig. 2, the truck. The guiding frame 4 forms an elongated guideway or track for the kerf cutting mechanism 5 along which the latter moves during the cutting operation, and this kerf cutting mechanism includes a frame or sliding support 20 having plane surfaces 21 slidably engaging the guide plates 19, 19, and the slidable cutting mechanism support is retained on the guiding frame by means of angle members 22, 22 attached to the sides of the sliding support 20 and underlying the outer flanges of the guide plates 19, 19 in the manner shown. It will thus be seen that the structure described above forms a sliding support for the kerf cutting mechanism and is slidable longitudinally of the guiding frame 4 between the ends thereof, as hereinafter described. It will be evident that, if desired, suitable anti-friction rollers may be provided between the cutting mechanism support 20 and the guiding frame and that various other arrangements may be employed for swivelly supporting the guiding frame on the truck and for guiding the cutting mechanism on the guide frame.

Now referring to the improved kerf cutting mechanism per se and more particularly to the driving mechanism for the cutting mechanism, it will be observed that keyed to the forward end of the motor power shaft 23, which is herein horizontally and longitudinally disposed, is a spur pinion 24 meshing with an idler gear 25 mounted on a stub shaft 26 carried by the front motor head 27, and this idler gear meshes with a spur gear 28 keyed to a splined shaft 29. The shaft 29 is horizontally disposed and extends longitudinally of the guiding frame 4 between the sides thereof, as shown in Fig. 6, and is journaled at its forward end within the front motor head 27 and at its rear end within a bearing sleeve 30 carried by a frame or bracket attached to the rear end of the guiding frame 4, as shown in Fig. 9. The shaft 29 is splined to and drives a hollow sleeve 31 through which the splined shaft extends, and this sleeve is suitably journaled within the sliding support 20. Formed on the sleeve 31 is a worm 32 meshing with a worm wheel 34. As shown in Figs. 3 and 4, the worm wheel 34 is provided with oppositely extending hub portions journaled within bearing sleeves 35, 36, the sleeve 36 being carried by a bracket 37 arranged within and secured to the sliding support 20. Formed on one hub of the worm wheel 34 are clutch teeth 38 which are connectible by a sliding clutch member 39 with clutch teeth 40 formed on a shaft 41 herein arranged with its axis alined with the worm wheel axis and journaled at its inner end within a bearing sleeve 41a positioned within the adjacent hub of the worm wheel. Keyed to the outer end of the shaft 41 is a sprocket 42 which

engages and drives, in a well known manner, a cutter bit carrying cutter chain 43 mounted on the margin of an elongated plane cutter bar 44 for circulation thereabout. As shown in Fig. 1, the cutter bar 44 is swingable in vertical planes at one side of the guiding frame 4 and is supported at its rear end by a cylindrical bar support 45 rotatably mounted within bearing sleeves 46, 47, the bearing sleeve 47 being supported by a bracket 48 secured to the sliding support 20 while the bearing sleeve 46 is positioned within a bore 49 formed in the adjacent side wall of the sliding support 20. This cylindrical bar support 45 carries the bearing sleeve 35 within which the hub of the worm wheel 34 is journaled, and is herein made up of three complementary parts comprising a centrally located member 50 attached, as by screws 51, to end members 52 and 53. The outer end of the shaft 41, as shown in Fig. 3, is journaled within a bearing 54 carried by the outer member 52 of the rotatable bar mounting 45.

The improved mechanism for swinging the cutter bar vertically in its plane and for feeding the kerf cutting mechanism back and forth along the guiding frame 4 herein comprises, as shown in Figs. 3, 4 and 5, a shaft 55 keyed, at 56, to the adjacent hub of the worm wheel 34. This shaft is journaled in bearings 57 and 58, the former being supported by the bearing bracket 37 while the latter is carried by a detachable cover plate 59 attached to the adjacent side wall of the sliding support 20. Rotatably mounted on the shaft 55 and connectible thereto by a multiple disc clutch 60 is a spur pinion 61 meshing at opposite sides thereof with spur gears 62 and 63 respectively keyed to parallel shafts 64 and 65 horizontally disposed and extending transversely of the sliding support 20. These shafts are journaled in bearings 66 and 67 carried by the bearing bracket 37 and detachable cover plate 59 respectively. Also rotatably mounted on the shaft 55 adjacent the opposite end thereof and connectible to the shaft by a multiple disc clutch 68 is a spur pinion 69 meshing with idler gears 70 and 71 (see Fig. 5) which in turn mesh with spur gears 72 and 73 keyed to the shafts 64 and 65 respectively. It will thus be seen that when the clutch 60 is applied and the clutch 68 is released, the shafts 64, 65 may be driven in one direction, and when the clutch 60 is released and the clutch 68 is applied, the shafts 64, 65 may be driven in the reverse direction. Suitably fixed to the shafts 64 and 65 respectively are worms 74 and 75, the former having teeth of steeper inclination than the latter, these worms meshing respectively with slow and fast speed worm wheels 76 and 77, as shown in Fig. 8. The worm wheels 76 and 77 are connectible by multiple disc clutches 78 and 79 respectively to a hollow shaft 80 herein arranged on a horizontal axis coincident with the worm wheel axes and extending longitudinally of and suitably journaled within the sliding support 20, and the shaft 80 may be driven through the worm gearing at relatively high and low speeds. Journaled on the sliding support 20 in axial alignment with and extending within and connectible to the shaft 80 are relatively rotatable shafts 81 and 82. The shaft 81 herein constitutes the feed driving shaft while the shaft 82 is the bar swing driving shaft, and the connection between the shaft 82 and the cutter bar herein comprises a worm 84 fixed to the shaft 82 and meshing with a worm wheel 85 (see also Fig. 4) keyed to a horizontal 75

shaft 86 herein arranged transversely of and journaled within the sliding support 20 and arranged at the rear of the bar pivot axis. Formed on the shaft 86 is a spur pinion 87 meshing with a gear segment 88 herein formed on the centrally located member 50 of the cylindrical bar support 45. It will thus be seen that the cutter bar 44 may be swung either upwardly or downwardly in a vertical direction at either a slow cutting speed or a high positioning speed under the control of the reverse frictions 60, 68 and the speed control clutches 78 and 79. When the bar swing controlling frictions 78 and 79 are released and the shafts 81 and 82 are disconnected from the shaft 80, the cutter bar is automatically locked in position by the self-locking worm gearing 84, 85. The mechanism for selectively connecting the shafts 81 and 82 to the shaft 80 will be hereafter described.

Now referring to the improved kerf cutter feeding mechanism, it will be observed that keyed to the shaft 81 is a spur gear 89 meshing, as shown in Fig. 10, with a spur gear 90 herein secured to a feed nut 91 suitably journaled within the sliding frame 20. This feed nut threadedly engages a non-rotatable feed screw 92 arranged parallel with the splined shaft 29 and likewise extending longitudinally of and suitably supported within the swiveled guiding frame 4. As shown in Fig. 6, the forward end of this feed screw 92 is supported within a detachable bracket 93 carried within the front motor head 27 and secured in position within the bracket by a nut connection 94. It will thus be seen that the kerf cutting mechanism may be fed at a slow cutting speed or a high positioning speed in either direction along the guiding frame 4 under the control of the reverse frictions 60, 68 and the speed control clutches 78 and 79. When the disc clutches 78 and 79 are released and the shafts 81 and 82 are disconnected from the shaft 80, the kerf cutting mechanism is automatically locked in position on the guiding frame by the self-locking threads of the coacting feed nut and screw.

The operating mechanism for the various clutches described above will now be described. As shown in Figs. 3 and 4, the sliding clutch 39 is connected by a transverse pin 95 guided in a slot 96 in the shaft 41, to an operating rod 97 extending centrally through the shaft 55 and having at its outer end an operating handle 98. It will thus be seen that when the handle 98 is moved inwardly or outwardly, the sliding clutch 39 is moved into its connected or released position. The reverse frictions 60, 68 are operated by sliding collars 99, 99 with which cooperates a shipper member 100 pivotally mounted at 101 on the sliding frame 20 as shown in Figs. 3 and 8. Pivotally connected to the shipper 100, at 102, is a rod 103 threadedly connected at 104 to a rotatable nut 105. The nut 105 is provided with a suitable operating handle 106. The disc clutches 78, 79 are operated respectively by annular clutch applying members 107 with which cooperates a pivoted shipper yoke 108. This shipper yoke is swung about its pivot by an actuating sleeve 109 having attached thereto a suitable handle 110, as shown in Fig. 3. When the clutch shipper member 108 is moved in one direction, one friction clutch is applied, and when the shipper member is moved in the opposite direction, this is released and the other clutch is applied.

The mechanism for connecting the shafts 81 and 82 selectively to the shaft 80 herein com-

prises interlocking mechanisms 111 and 112 respectively. These interlocking mechanisms are identical in construction and comprise, as shown in Figs. 3 and 8, radially located plungers 113 movable into interlocking engagement with grooves 114 formed in the shafts 81, 82. An annular member 115 is provided for actuating the interlocking plungers and has cam surfaces 116 engageable with corresponding inclined surfaces on the interlocking plungers. It will thus be seen that when the member 115 is moved in one direction, the cam surfaces 116 thereon force one set of the plungers into interlocking engagement with the grooves on one of the shafts and at that time the other plungers are released. These interlocking mechanisms entirely release the shafts 81, 82 from the friction clutches so that when the friction clutches are released, the drag rotation, which is always present, will not tend to effect undesired rotation of the shafts. It will thus be seen that the shafts 81 and 82 may be selectively connected to the shaft 80 and may be driven by the latter at either high or low speeds. The operating means for the member 115 comprises, as shown in Fig. 3, a pivoted shipper yoke 117 supported by a shaft 118 carrying a handle 119, it being noted that the shipper yoke 108 for the clutch control members 107 is swingably mounted on the shaft 118 as shown. Suitable spring means to facilitate withdrawal of the members 111 and 112 and to hold them in disconnecting position may advantageously be used.

The mechanism for driving the truck wheels to propel the apparatus along the mine trackway herein comprises a spur pinion 120 fixed to the rearward end of the motor shaft 23, as shown in Figs. 6 and 7, and meshing with a spur gear 121 which drives a spur gear 122 in turn meshing with a spur gear 123 keyed to a longitudinally extending shaft 124 housed within a sleeve and suitably journaled on the swiveled guiding frame 4, as shown in Fig. 6. Keyed to the shaft 124, at its rear end, is a worm 125 meshing with a worm wheel 126 keyed to a vertical shaft 127 arranged with its axis coincident with the swivel axis of the guiding frame 4, as shown in Fig. 7. Keyed to the lower end of the shaft 127 is a bevel pinion 128 meshing, as shown in Fig. 3, with reverse bevels 129, 130. These reverse bevels are selectively connectible to the front truck wheel axle 15 by multiple disc clutches 131, 132 respectively. It will thus be seen that when the clutch 130 is applied, the apparatus may be fed along the mine trackway in one direction, and when this clutch is released and the clutch 132 is applied, the machine may be propelled along the mine trackway in the reverse direction. The operating means for the friction clutches 131, 132 includes a slidable clutch applying member 133 with which a pivoted shipper yoke 134 cooperates. The swinging means for the shipper yoke comprises, as shown in Fig. 1, a longitudinally extending rod 135 having attached thereto, at its rear end, an operating lever 136 conveniently located at the rear end of the truck frame.

A truck wheel brake comprising a brake drum 137 is provided for braking the truck wheels, and this brake is operated through suitable operating connections including a pivoted brake lever 138. Mounted on the rear portion of the truck frame is a suitable electrical control apparatus 139 and a conductor cable reeling device 140. The cable reel is driven through a chain and sprocket connection 141 connected to the rear truck wheel 75

axle, as shown in Fig. 2, under the control of a clutch 142 having a control handle 143. The general mode of operation of the improved mining apparatus will now be briefly described.

5 The apparatus is propelled about the mine at a relatively fast transport speed through the gear connections 120, 121, 122, and 123 and worm gearing 125, 126 under the control of the reverse frictions 131, 132. When the working face is 10 reached the friction clutch controlling the high speed truck drive is released and the truck wheel brake 137 is set, locking the truck wheels against rotation. If it is desired to insert a shear cut in the coal directly in advance of the guiding frame 2 15 when the parts are in the position shown in Figs. 1 and 2, the friction clutch 79 is applied and the interlocking mechanism 112 connected, and upon suitable application of the reverse frictions 60, 68, the cutter bar is swung upwardly to a position 20 wherein its outer extremity is adjacent the mine roof at the face, the clutches and interlock thereafter being released. The cutter bar is automatically maintained in its adjusted position by the self-locking worm gearing 84, 85. The operator 25 then actuates the handle 98 to connect the cutter chain clutch 39, thereby connecting the cutter chain in driving relation with the motor, and as a result the cutter chain 43 is rapidly circulated about the margin of the cutter bar 44. The friction clutch 78 is then applied and the interlock 111 connected, and upon suitable application of the reverse frictions 60, 68, the feed nut 91 is 30 rotated relative to the stationary feed screw 92, and as a result the kerf cutting mechanism is fed 35 at a slow cutting speed bodily along the relatively stationary guiding frame 4, sumping the cutter bar within the coal. Upon completion of the sumping cut the friction clutch 78 and interlock 111 are released and the interlock 112 connected, and upon application of the friction clutch 78 and the proper reverse frictions 60, 68, the cutter bar is swung downwardly in its plane 40 at a slow cutting speed to effect its vertical swinging cut, the clutch and interlock thereafter being released. The clutch 78 and interlock 111 are 45 then again connected, and upon application of the proper reverse friction the cutting mechanism is fed bodily rearwardly along the stationary guiding frame 4 at a slow cutting speed, withdrawing the 50 cutter bar from the coal. Upon completion of the withdrawal cut the bar swing is reversed and the cutter bar swung upwardly into its transport position shown in Fig. 2. The truck wheel brake is then released and upon proper application of 55 the truck drive controlling frictions 131, 132 the apparatus is propelled bodily rearwardly along the mine trackway away from the coal face at a transport speed. If it is desired to insert a shear cut at various angles relative to the central 60 longitudinal vertical plane of the machine, this may be accomplished simply by swinging the swiveled frame 4 relative to the truck frame to bring the cutter bar into the desired angular position. For instance, the guiding frame 4 may 65 be swung into a position at right angles to the trackway, and when so positioned the cutter bar may be swung upwardly, fed rectilinearly to effect its sumping cut, swung downwardly in its plane, and thereafter fed rectilinearly rearwardly to 70 effect its withdrawal cut in the manner described above. It will be noted that during any of aforesaid operations the cutter bar may be swung and the cutting mechanism may be fed in either direction at either a high or a low speed under the 75 control of the speed control clutches 78 and 79

and the interlocking mechanisms 111, 112. These and other operations and advantages of the improved mining apparatus will be clearly apparent to those skilled in the art.

While there is in this application specifically described one form which the invention may assume in practice, it will be understood that this form of the invention is shown for purposes of illustration and that the invention may be modified and embodied in various other forms without departing from its spirit or the scope of the appended claims.

What I claim as new and desire to secure by Letters Patent is:

1. In a mining apparatus, a portable base, a 15 horizontal guiding frame swiveled on said base, kerf cutting mechanism supported on said guiding frame for movement therealong and including a pivoted kerf cutter swingable relative to said frame, a motor supported on the forward end 20 of said guiding frame in advance of said base and relative to which said kerf cutting mechanism is movable, the frame guideway extending rearwardly of said motor and overlying said base, and driving connections between said motor and said 25 kerf cutting mechanism.

2. In a mining apparatus, a portable base, a horizontal guiding frame swiveled about a vertical axis on said base, kerf cutting mechanism supported on said guiding frame for rectilinear 30 movement along the length thereof and including a pivoted kerf cutter swingable relative to said frame, a motor supported on said guiding frame out of the path of movement of said kerf cutting mechanism and relative to which said kerf cutting 35 mechanism is movable, driving connections between said motor and said kerf cutting mechanism, and mechanism driven by said motor for propelling the apparatus.

3. In a mining apparatus, a portable base, a 40 horizontal guiding frame having a swivel mounting at the forward end of said base, the rearward portion of said guiding frame overlying the base and the forward portion thereof extending a substantial distance in advance of the base, kerf 45 cutting mechanism guided on said frame for movement therealong, and a motor supported on the forwardly extending portion of said guiding frame for driving the kerf cutting mechanism.

4. In a mining apparatus, a portable base, a 50 horizontal guiding frame swiveled on said base, kerf cutting mechanism mounted on said guiding frame for movement therealong, a motor suspended beneath said guiding frame and stationary as regards movement relative to said frame, 55 and mechanism driven by said motor for driving said kerf cutting mechanism.

5. In a mining apparatus, a portable base, a guiding frame on said base and having a longitudinal guideway, a motor on the forward end of 60 said guiding frame stationary as regards movement relative thereto, said guideway extending rearwardly with respect to said motor, kerf cutting mechanism mounted on the guideway of said guiding frame for movement therealong and including a pivoted kerf cutter swingable relative to said frame, and devices driven by said motor for feeding said kerf cutting mechanism relative to said guiding frame.

6. In a mining apparatus, a portable base, a 70 guiding frame on said base and having its forward extremity overhanging the forward end of said base and its rearward portion overlying said base, a motor on the forward overhanging end of said guiding frame stationary as regards move- 75

ment relative thereto, kerf cutting mechanism mounted on said guiding frame for movement therealong and including a pivoted kerf cutter swingable relative to said frame, devices driven by said motor for driving said kerf cutting mechanism, and devices driven by said motor for feeding said kerf cutting mechanism relative to said guiding frame.

5 7. In a mining apparatus, a portable base, a guiding frame on said base and having a longitudinal guideway, a motor on the forward end of said guiding frame stationary as regards movement relative thereto, said guideway extending rearwardly with respect to said motor, kerf cutting mechanism mounted on the guideway of said guiding frame for movement therealong and including a swingable kerf cutter, and devices driven by said motor for driving said cutting mechanism and for swinging said kerf cutter.

10 8. In a mining apparatus, a portable base, a guiding frame on said base and having its forward extremity overhanging the forward end of said base and its rearward portion overlying said base, a motor on the forward overhanging end of said guiding frame stationary as regards movement relative thereto, kerf cutting mechanism mounted on said guiding frame for movement therealong and including a swingable kerf cutter, devices driven by said motor for driving said cutting mechanism and for swinging said kerf cutter, and devices driven by said motor for feeding said cutting mechanism relative to said guiding frame.

15 9. In a mining apparatus, a portable base, a guiding frame on said base having a longitudinal guideway, a motor on the forward end of said guiding frame between the ends of the latter and below the top surface of said guideway, said motor being stationary as regards movement relative to said frame, kerf cutting mechanism mounted on said guiding frame for movement along the guideway thereof and including a swingable kerf cutter, devices driven by said motor for driving said cutting mechanism and for swinging said kerf cutter relative to the guiding frame, devices driven by said motor for feeding said cutting mechanism relative to said guiding frame, and devices driven by said motor for propelling the apparatus.

20 10. In a mining apparatus, a portable base, a horizontal guiding frame swiveled on said base and projecting forwardly in advance of said base, kerf cutting mechanism supported on said guiding frame for movement therealong and including a pivoted kerf cutter swingable relative to said frame, a motor supported on said guiding frame in advance of said base and relative to which said kerf cutting mechanism is movable, driving connections between said motor and said kerf cutting mechanism, and mechanism driven by said motor for swinging said kerf cutter about its pivot relative to said guiding frame.

25 11. In a mining apparatus, a portable base, a horizontal guiding frame swiveled on said base and projecting forwardly in advance of said base, kerf cutting mechanism supported on said guiding frame for movement therealong and including a pivoted kerf cutter swingable relative to said frame, a motor supported on said guiding frame in advance of said base and relative to which said kerf cutting mechanism is movable, driving connections between said motor and said kerf cutting mechanism, mechanism driven by said motor for propelling the apparatus, and mechanism driven by said motor for swinging

said kerf cutter about its pivot relative to said guiding frame.

30 12. In a mining apparatus, kerf cutting mechanism including a pivoted kerf cutter, and mechanism for swinging said kerf cutter and for feeding said kerf cutter including coaxial relatively rotatable high and low speed gears, clutches coaxial with said gears controlling drive by said gears respectively, and clutches coaxial with said clutches for connecting either said swinging mechanism or said feeding mechanism in driving relation with said gears for drive by the latter.

35 13. In a mining apparatus, kerf cutting mechanism including a pivoted kerf cutter, and mechanism for swinging said kerf cutter and for feeding said kerf cutter at either a high or a low speed including coaxial relatively rotatable high and low speed gears, clutches controlling drive by said gears respectively, a kerf cutter swinging element and a relatively rotatable kerf cutter feeding element both coaxial with said gears, and clutches for connecting either said swinging mechanism element or said feeding mechanism element in driving relation with said gears for drive by the latter.

40 14. In a mining apparatus, kerf cutting mechanism including a pivoted kerf cutter, and mechanism for swinging said kerf cutter and for feeding said kerf cutter including coaxial relatively rotatable high and low speed gears, relatively rotatable shafts coaxial with said gears, connections between one of said shafts and said kerf cutter swinging mechanism, connections between the other of said shafts and said kerf cutter feeding mechanism, and interlocking clutch mechanism coaxial with said gears for connecting either shaft in driving relation with either gear for drive by the latter.

45 15. In a mining apparatus, kerf cutting mechanism including a pivoted kerf cutter, and mechanism for swinging said kerf cutter in either of opposite directions about its pivot including a driving element arranged with its axis parallel to a line parallel with the cutter pivot axis, a shaft coaxial therewith and driven thereby, gears coaxial with said shaft, clutches for selectively connecting said gears to said shaft, and driving connections between said gears respectively and said kerf cutter, one driving connection effecting kerf cutter swing in one direction and the other driving connection effecting kerf cutter swing in the opposite direction.

50 16. In a mining apparatus, kerf cutting mechanism including a pivoted kerf cutter, and mechanism for swinging said kerf cutter in either of opposite directions at either a relatively high speed or a relatively low speed including a driving element arranged with its axis parallel to a line parallel with the cutter pivot axis, a shaft coaxial therewith and driven thereby, gears coaxial with said shaft, clutches for selectively connecting said gears to said shaft, a high speed swing-effecting driving connection between one of said last mentioned gears and said kerf cutter, and a low speed swing-effecting driving connection between the other of said last mentioned gears and said kerf cutter.

55 17. In a mining apparatus, kerf cutting mechanism including a pivoted kerf cutter, mechanism for swinging said kerf cutter in either of opposite directions at either a relatively high or a relatively low speed including a driving element, a shaft coaxial therewith and driven thereby, gears coaxial with said shaft, clutches for selectively connecting said gears to said shaft, con- 70

75

nections driven by said gears respectively to effect drive in reverse directions, a high speed driving connection, and a low speed driving connection, said high and low speed driving connections being driven in either of opposite directions through 5 said first mentioned driving connections.

18. In a mining apparatus, a kerf cutting mechanism including a pivoted kerf cutter, mechanism for actuating said kerf cutter including a driving element alined with the kerf cutter pivot, and mechanism driven by said driving element including a shaft alined with said driving element, relatively rotatable gears coaxial with said shaft, clutches for selectively connecting said gears to 10 said shaft, parallel shafts, connections between one of said gears and said parallel shafts for driving said shafts in one direction, connections between the other of said gears and said parallel shafts for driving said shafts in the opposite direction, means for swinging said kerf cutter about 15 its pivot including a kerf cutter swinging element, means for feeding said kerf cutter including a kerf cutter feeding element, and driving connections between said parallel shafts and said kerf cutter swinging and feeding elements.

19. In a mining apparatus, kerf cutting mechanism including a pivoted kerf cutter, mechanism for actuating said kerf cutter including a driving element alined with the kerf cutter pivot, and mechanism driven by said driving element for swinging said kerf cutter about its pivot including a shaft alined with said driving element and driven thereby, relatively rotatable gears coaxial with said shaft, clutches for selectively connecting 20 said gears to said shaft to effect driving thereof by said shaft, a shaft parallel with said shaft, a kerf cutter swinging element driven by said parallel shaft, connections driven by one of said gears for driving said parallel shaft in one direction, and connections driven by the other of said gears for driving said parallel shaft in the reverse direction.

20. In a mining apparatus, kerf cutting mechanism including a pivoted kerf cutter, mechanism for actuating said kerf cutter including a driving element alined with the kerf cutter pivot, and mechanism driven by said driving element for swinging said kerf cutter about its pivot including a shaft coaxial with said driving element and driven thereby, a parallel shaft, a kerf cutter swinging element driven by said parallel shaft, a fast speed gear train and a slow speed gear train, clutch mechanism for connecting said gear trains in driving relation 25 with said coaxial shaft to effect driving thereof by said coaxial shaft, and driving connections between said gear trains and said parallel shaft.

21. In a mining apparatus, kerf cutting mechanism including a pivoted kerf cutter, mechanism for actuating said kerf cutter including a driving element alined with the kerf cutter pivot, and mechanism driven by said driving element for swinging said kerf cutter about its pivot including a shaft coaxial with said driving element and driven thereby, relatively rotatable gears coaxial with said shaft, clutches for selectively connecting said gears to said shaft, parallel shafts, driving connections between one of said gears and said parallel shafts for driving the latter in one direction, driving connections between the other of said gears and said parallel shafts for driving the latter in the opposite direction, a shaft parallel with said shafts, a kerf cutter swinging element driven by said last 30 mentioned parallel shaft, and high and low speed

driving connections between said first mentioned parallel shafts respectively and said last mentioned parallel shaft.

22. In a mining apparatus, kerf cutter feeding mechanism including a kerf cutter feeding element, and driving means for said feeding element for driving the latter in either of opposite directions including a shaft, relatively rotatable gears coaxial with said shaft, clutches for selectively connecting said gears to said shaft, a pair 5 of parallel shafts, driving connections between one of said gears and said parallel shafts for driving the latter in one direction, driving connections between the other of said gears and said parallel shafts for driving the latter in the opposite direction, and driving connections between said parallel shafts and said feeding element.

23. In a mining apparatus, a portable base, a horizontal guiding frame swivelly mounted on 10 said base for horizontal swinging movement relative thereto, the rearward portion of said guiding frame overlying the base and the forward portion thereof extending a substantial distance 15 in advance of the base, kerf cutting mechanism 20 guided on said frame for movement therewith, and a motor supported on the forwardly extending portion of said guiding frame for driving the kerf cutting mechanism, said kerf cutting mechanism movable relative to said motor and said 25 motor being so arranged on said guiding frame as to substantially counter-balance the weight 30 of the cutting mechanism when the latter is in its rearward position on said guiding frame.

24. In a mining apparatus, a portable base, a horizontal guiding frame swiveled on said base for horizontal swinging movement relative thereto, kerf cutting mechanism mounted on said 35 guiding frame for movement therewith, a motor supported beneath said guiding frame and stationary as regards movement relative to said frame, and mechanism driven by said motor for driving said kerf cutting mechanism, said kerf cutting mechanism overlying said motor in one 40 position on said guiding frame.

25. A mining apparatus, a frame, a kerf cutter thereon, and means for feeding the frame to effect feeding movement of the kerf cutter including a feed operating member and motor operated mechanism for driving said member at 45 either of two relatively different predetermined speeds and in either direction at either speed including reversing gearing including relatively rotatable shafts disposed on horizontal axes extending transversely of said frame, a horizontal 50 shaft disposed on a horizontal axis extending longitudinally of said frame and operatively connected to said feed operating member, and fast and slow speed gearing between said reversing 55 gearing and said longitudinally extending shaft.

26. A mining apparatus, a frame, a kerf cutter mounted thereon for swinging movement relative thereto, and means for feeding the frame to effect feeding movement of the kerf cutter including a feed operating member, motor operated 60 mechanism for driving said member at either of two relatively different predetermined speeds and in either direction at either speed including reversing gearing including relatively rotatable shafts disposed on horizontal axes extending 65 transversely of said frame, a horizontal shaft disposed on a horizontal axis extending longitudinally of said frame and operatively connected to said feed operating member, and fast and slow speed gearing between said reversing 70 gearing.

and said longitudinally extending shaft, and mechanism including a shaft coaxial with said longitudinally extending shaft and driven through said fast and slow speed gearing for swinging said kerf cutter.

27. In a mining apparatus, a frame, a kerf cutter pivotally mounted thereon, means for feeding said frame, and motor operated mechanism for swinging said kerf cutter and for driving said feeding means including coaxially arranged relatively rotatable elements, one connected to the feeding means and the other to the kerf cutter swinging mechanism, fast and slow speed gearing for driving said elements, and clutch mechanisms for connecting either driving element in driving relation with said gearing.

28. In a mining apparatus, a frame, a kerf cutter pivotally mounted thereon, means for feeding said frame, and motor operated mechanism for swinging said kerf cutter and for driving said feeding means including alined relatively rotatable shafts one operatively connected to said feeding means and the other operatively connected to the mechanism for swinging the kerf cutter, fast and slow speed driving mechanism including relatively rotatable fast and slow speed gears coaxial with said shafts, and clutch mechanism for connecting either gear in driving relation with either shaft. 5

MORRIS P. HOLMES. 15
